FIRE EXTINGUISHER

Joshua Gordon Lippincott, Scarsdale, N. Y., and
Laird F. Covey, Darien, Conn., assignors to The
Fyr-Fyter Company, Dayton, Ohio, a corpora-
tion of Ohio

Application May 16, 1950, Serial No. 9,972

Term of patent 14 years

(Cl. D16—2)

To all whom it may concern:

Be it known that we, Joshua Gordon Lippincott and Laird F. Covey, citizens of the United States of America, residing at Scarsdale, in the county of Westchester and State of New York, and Darien, in the county of Fairfield and State of Connecticut, respectively, have invented a new, original, and ornamental Design for a Fire Extinguisher, of which the following is a specification, reference being had to the accompanying drawing, forming a part thereof.

Fig. 1 is a perspective view of a fire extinguisher embodying our new design;

Fig. 2 is a top plan view of the extinguisher;

Fig. 3 is a fragmentary view in side elevation of the extinguisher; and

Fig. 4 is a fragmentary view in rear elevation of the extinguisher.

The design is characterised by the parts shown in full lines in the drawing.

We claim:

The ornamental design for a fire extinguisher, substantially as shown and described.

JOSHUA GORDON LIPPINCOTT.
LAIRD F. COVEY.
